(57) **CLAIM**

The ornamental design for an icosahedral chart of the 20 commonly occurring amino acids, as shown.

DESCRIPTION

FIG. 1 is a front view of the icosahedral chart of the 20 commonly occurring amino acids.

FIG. 2 is a back view of the icosahedral chart.

FIG. 3 is a right view of the icosahedral chart.

FIG. 4 is a left view of the icosahedral chart.

FIG. 5 is a top view of the icosahedral chart.

FIG. 6 is a bottom view of the icosahedral chart.

FIG. 7 is a cut-and-assemble pattern of the right bottom half of the icosahedral chart; and,

FIG. 8 is a cut-and-assemble pattern of the left top half of the icosahedral chart.
